BUMPER

Robert O. Hein and Norbert Shaeffer, Chicago,
Ill., assignors to Sears, Roebuck and Co., Chi-
cago, Ill., a corporation of New York

Application August 26, 1937, Serial No. 161,000

5 Claims. (Cl. 15—257)

This invention relates to bumpers and is concerned more particularly with vacuum cleaners and other devices susceptible to injury by collision with, and likely to injure, furniture and other bodies.

In the use of a vacuum cleaner and other apparatus moved among furniture and other objects, the casing oftentimes strikes the objects with such force as to injure both.

It is accordingly an object of our invention to provide the vacuum cleaner or other movable apparatus adapted to be projected at least partially under furniture or the like with bumper means.

It is another object to provide a vacuum cleaner or the like dome or other casing with means for protecting the casing against collision injury.

Another object is to provide a resilient bumper element adapted to retain itself in assembly with a part to be protected thereby.

A further object is to provide a bumper for the motor casing of a vacuum cleaner or the like.

It is a further object to provide a single rubber or the like bumper element adapted to protect a motor casing dome and provide a protective frame for a utility light in the dome.

Further objects and advantages of the invention will appear as the description proceeds.

On the accompanying drawing:

Fig. 1 is a fragmentary front elevation of a vacuum cleaner equipped with a bumper embodying my invention.

Fig. 2 is an enlarged fragmentary side elevation of the motor and fan casing of Fig. 1.

Fig. 3 is an enlarged fragmentary longitudinal section through the bumper structure of our invention, taken as indicated by the line 3—3 in Fig. 1.

Fig. 4 is a sectional view taken substantially along line 4—4 of Fig. 3.

Figs. 5 and 6 are fragmentary sectional views taken as indicated by the lines 5—5 and 6—6, respectively, in Fig. 3.

Fig. 7 is a fragmentary plan view of the upper portion of the casing.

Fig. 8 is an enlarged fragmentary sectional view taken as indicated by the line 8—8 in Fig. 1.

Referring now more particularly to the drawing, for the purpose of illustration we have shown a vacuum cleaner the operating mechanism of which is housed in a casing 10 comprising a base or substructure 11 which may contain the blower or fan (not shown) and a superstructure in the form of a dome 12 adapted to enclose the motor (not shown). The dome 12 is disposed prefer-

ably well to the rear of the front end 13 of the casing base so as to allow said end, which at the bottom has a suction inlet (not shown), to be projected a substantial distance under daventry and other open bottom furniture and other objects for cleaning thereunder, as indicated at A in Fig. 2. The front and sides of the casing base may be equipped with a resilient bumper strip B for engagement with parts extending substantially to the floor. A utility lamp (not shown) may be provided behind the window or opening 14 at the front of the dome.

The dome 12 because of its projection above the base will collide with raised parts of furniture and other objects as shown at C in Fig. 2, and unless suitable protection were provided, the colliding members would be marred. To safeguard against this is a salient object of my invention.

20 To this end, the dome may have a groove or channel 16 extending forward and downward from the top 17 and terminating at the upper side 18 of the frame opening 14. At the upper end of the channel there is a hole 20 extending through the dome. Although this hole may be of any suitable shape, it is preferably dovetailed with increasing width inward as shown in Figs. 3 and 5. The channel may have any suitable shape and, as shown, may have an enlarged portion 21 of reduced width adjacent the hole 20.

A bumper embodying our invention may comprise the rubber or other preferably resilient element 22 of any suitable shape. In the illustrated embodiment, where the dome has the utility light opening 14, the bumper element may advantageously have the shape of a T, with its stem 23 fitting in the channel 16 and its hollow head 24 fitting in the frame opening 14. The free end 26 of the stem may be formed with a downwardly projecting boss 27 shaped preferably to conform with the hole 20 at the top of the dome 12. Accordingly it will be observed that the boss 27 is compressed as it is forced down through the hole 20 to occupy the position shown, where it is firmly anchored to the dome. From this point forward and downward the element is fitted in the channel.

The head 24 of the element may be in the shape of a frame of strip material. The strip may be 50 U-shaped in cross section with the groove 29 opening outwardly and dimensioned to snugly receive the dome edge 30 defining the opening 14. The back flange 31 of the head 24 is an enlargement which cooperates with the dome at the opening 14 in substantially dovetail fashion,

anchoring the lower end of the bumper element to the dome.

It will be observed that the bumper element may be substantially 90 degrees in extent relative to the dome and, preferably throughout its entire length, the bumper element projects outward relative to the adjacent surface portions of the dome, as shown at 33. The element has a substantially tongue-and-groove connection with the dome and projects forward of the foremost part of the dome so that it affords protection when a relatively low surface, as seen dotted at C', is struck, and it projects to or slightly above the top of the dome so as to afford protection when a relatively high surface, as seen dotted at C'', is struck.

It is evident that only a moment's time is needed to apply and securely anchor the bumper element to the dome, the element being preferably formed to have a firm snug fit. Its outer surface may be tapered or otherwise formed so as to have esthetic as well as utilitarian value. By substantially merging the sides 36 of the stem 23 with the adjacent surfaces of the dome, likelihood of forcing the stem out of the dome channel upon sidewise engagement with an object is obviated. The element may be stretched somewhat between its ends and preferably fills and may overlap a part of the channel at the mouth thereof to prevent lodging of particles of dust and the like.

We are aware that reversals of parts may be resorted to, and that many changes may be made and numerous details of construction may be varied through a wide range without departing from the principles of this invention, and we therefore do not purpose limiting the patent granted hereon otherwise than as necessitated by the prior art.

We claim:

1. A vacuum cleaner or the like comprising a dome-like casing having an opening in the top thereof and a window at the front thereof for passage of light from a lamp to be mounted in the casing, and a rubber or other resilient element having a tongue-and-groove fit with said casing between said opening and said window and having a boss sprung into said opening so as to anchor said element, said element having a rearwardly disposed enlargement sprung through said window and engaged with the rear side of the casing front so as to additionally anchor said element.
2. In combination, a portable tool having a window opening therein, an elongated entirely resilient bumper detachably secured on said tool

5 by reason of the distortability of said bumper, said bumper including frame-like means at one end thereof and substantially conforming with and overlapping the edge of said window opening to provide an anchorage for one end of said bumper, said bumper also having an integral enlargement at its opposite end retained by said tool so as to provide an anchorage for that end of the bumper.

3. In combination, a portable tool having a window opening therein, an elongated entirely resilient bumper detachably secured on said tool by reason of the distortability of said bumper, said bumper including frame-like means at one end thereof and substantially conforming with and overlapping the edge of said window opening to provide an anchorage for one end of said bumper, said bumper also having an integral enlargement at its opposite end retained by said tool so as to provide an anchorage for that end of the bumper, said tool and said bumper being formed to provide interlocking detachable engagement therebetween intermediate of said anchorages.

4. In combination, a portable tool having a window opening therein and a second opening spaced therefrom, an elongated resilient bumper detachably secured on said tool by reason of its distortability, frame-like means integral with said bumper at one end thereof and substantially conforming with and overlapping the edge of said window opening to provide an anchorage for one end of said bumper, said bumper also having an integral enlargement at its opposite end sprung through said opening and retained by said tool so as to provide an anchorage for that end of the bumper.

5. In combination, a portable tool having a window opening therein and a second opening spaced therefrom, an elongated resilient bumper detachably secured on said tool by reason of its distortability, frame-like means integral with said bumper at one end thereof and substantially conforming with and overlapping the edge of said window opening to provide an anchorage for one end of said bumper, said bumper also having an integral enlargement at its opposite end sprung through said opening and retained by said tool so as to provide an anchorage for that end of the bumper, said tool and said bumper being formed to provide interlocking detachable engagement therebetween intermediate of said anchorages.
